US00D937515S

(12) United States Design Patent (10) Patent No.: US D937,515 S
(45) Date of Patent: * Nov. 30, 2021

(54) WASHING MACHINE

(71) Applicant: Samsung Electronics Co., Ltd.,
Suwon-si (KR)

(72) Inventors: Jinnam Kim, Suwon-si (KR); Hayong Jang, Suwon-si (KR); Ilmo Ahn, Suwon-si (KR); Dongwon Chun, Suwon-si (KR)

(73) Assignee: Samsung Electronics Co., Ltd.,
Suwon-si (KR)

() Term: 15 Years

(21) Appl. No.: 29/702,484

(22) Filed: Aug. 20, 2019

(30) Foreign Application Priority Data

Mar. 11, 2019 (KR) 30-2019-0010884

(51) LOC (13) Cl. 15-05

(52) U.S. Cl. D32/28
USPC .....

(58) Field of Classification Search

USPC D32/1, 8, 25, 28; D15/89

CPC D06F 34/28; D06F 39/083; G06F 3/0482

See application file for complete search history.

(57) CLAIM

We claim the ornamental design for a washing machine, as shown and described.

DESCRIPTION

FIG. 1 is a front perspective view of a washing machine showing our new design according to a first embodiment;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view of a washing machine showing our new design according to a second embodiment;

FIG. 9 is a front view thereof;

FIG. 10 is a rear view thereof;

FIG. 11 is a left-side view thereof;

FIG. 12 is a right-side view thereof;

FIG. 13 is a top view thereof; and,

FIG. 14 is a bottom view thereof.

The broken lines in the figures depict portions of the washing machine which form no part of the claimed design.

1 Claim, 14 Drawing Sheets
